C. A. BUNKER.
BOTTLE CAPPING IMPLEMENT.
APPLICATION FILED JUNE 1, 1920.

1,362,776.

Patented Dec. 21, 1920.

UNITED STATES PATENT OFFICE.

CHARLES A. BUNKER, OF KANSAS CITY, MISSOURI.

BOTTLE-CAPPING IMPLEMENT.

1,362,776.

Specification of Letters Patent. Patented Dec. 21, 1920.

Application filed June 1, 1920. Serial No. 385,537.

To all whom it may concern:

Be it known that I, CHARLES A. BUNKER, a citizen of the United States of America, residing at Kansas City, in the county of Jackson and State of Missouri, have invented certain new and useful Improvements in Bottle-Capping Implements; and I do hereby declare that the following is a full, clear, and exact description of the invention, reference being had to the accompanying drawings, forming a part of this specification.

The invention is particularly designed to automatically grasp the neck of the bottle while the cap is being applied, thereby facilitating the bottle capping operation, and at the same time enabling the application of the cap and the sealing of the neck of the bottle, and the securing of the cap to the neck of the bottle, to be made with uniform efficiency.

The invention also embodies,

First, a coaction of the bottle grasping means with cap affixing means, whereby the cap is secured to the neck of the bottle without torsion, and,

Second, wherein the cap is held in position previous to its being fastened to the neck of the bottle, and

Third, to effect the disengagement of the bottle capping devices from the cap, and at the same time depress the center of the cap so as to force the packing into the neck of the bottle.

The invention consists in the novel construction and combination of parts such as will be first fully described, and then specifically pointed out in the claims.

In the drawings,

Figure 1 is an isometric view of the novel capping implement showing the lever arms in an elevated position, and the jaws of the device in an open position in readiness to grasp the neck of the bottle, a portion of the cap affixing body being broken away.

Fig. 2 is a plan view of the device as seen in Fig. 1, and

Fig. 3, is a view of the invention looking upwardly from beneath the bottle capping body the lever arms being in the same position as in Fig. 1.

Fig. 4, is a view in elevation partly in section showing the hand levers in a downward horizontal position and the jaws grasping the neck of the bottle and the position

of the cap disengaging plunger, while the cap is being secured to the neck of the bottle.

Fig. 5 is an isometric view enlarged of the hollow cap affixing body of the bottle capping implement, showing the cap holding flanges the outer end portions of the arms being broken away.

Fig. 6, is a detail view of one of the jaws and its supporting bar, showing the slot for the pivots on the inner ends of the lever arms.

Fig. 7, is a view of a cap for the bottle, broken away to show the packing.

Fig. 8, is a sectional view of the neck of the bottle, showing the cap secured thereto and the position of the packing relative to the opening in the neck.

Similar numerals of reference indicate corresponding parts in all the figures of the drawings.

The body of the implement consists of a circular casting 10, having an upwardly cone shaped extension 11. Within the body 10, is a circular opening or depression 12, slightly larger in circumference than the neck of the bottle to be capped, and of a depth sufficient to receive a portion of the end of the bottle above the neck, the terminus of said opening being curved or arched upwardly in a slight degree as at 13.

Through the cone-shaped portion 11, of the body 10 of the implement, extends an opening 14, which leads within the opening 12 of said body portion, and is co-axial with the inner circumference of said opening. With the body portion 10 of the implement, and connected integrally with one side, are the inner ends of separate arms 15-15' spaced a short distance apart, the outer ends of which arms extend outwardly a short distance and are extended downwardly in a curved line to a position a short distance below a line extending horizontally with the lower surface of the body portion 10, and in 100 said ends of the arms are perforations 15°. Similar arms 16-16' are connected integrally with the body 10 of the implement upon its other or opposing side, which are spaced apart, and are in line with the arms 15-15' and are precisely the same. The arms 16, 16', are provided with perforations 16°.

In the opening 14 in the cone-shaped upward extension of body 10, is a slideable rod 110

or plunger 17, the forward and rear surfaces of the upper end of said rod being cut away at 17^x.

18 and 19 indicate the grasping jaws for grasping the neck of the bottle. These jaws consist of oppositely positioned blocks of considerable thickness to afford the necessary rigidity and having their inner surfaces curved in the arc of a circle, as at 18° 10 19° respectively.

These blocks are integrally connected with the inner portions of separate inwardly and outwardly movable flat bars 20 and 21 respectively, these bars having their outer portions 15 extending short distances outwardly from the outer surfaces of the blocks to form lever bearings, as further described. The lower ends of these bars with the jaws 18 and 19 in their open position, as seen in Fig. 1, are in a position 20 below the body 10 to enable the jaws to grasp the neck of the bottle. From the jaws 18 and 19, the bars 20 and 21 extend upwardly between the respective arms 15—15' and 16—16' with a slight inclination 25 inwardly to the points 20° 21°, at which points the upper portion of bar 21 is bent forwardly and that of bar 20 is bent rearwardly slight distances out of line with the lower end of said bars. From said points 30 upwardly, the bars are inclined inwardly in a slight digress and the upper terminal or end portions of said bars 20' 21' bent horizontally and extended inwardly and secured by the pivot 20* to the respective forward and 35 rear flat surfaces of the upper end of the plunger 17.

Upon the opposite surfaces of the lower portions of the combined jaw and plunger operating bars 20 and 21, are cast the flat plates 20* 21*. These plates extend upwardly from the lines of the outer portions of the jaws 20 and 21, as shown in vertical lines, nearly to the bending points 20° 21° of said bars, and act as frictional guides to 40 the bars 20 and 21 upon the inner surfaces of the arms 15—15', 16 and 16', the outer edges of said plates at their lower ends serving as bearings for cam shaped ends of the operating levers 22 and 23.

50 These levers 22 and 23, are each formed from a single flat longitudinal bar of suitable material, preferably steel, bent between its ends to form an outer curved portion or loop 22*—23* parallel portions of which levers extend outwardly a considerable distance, their inner ends being outwardly curved at 24 to form cams.

In the lower outer portions of the bars 20 and 21, and a short distance upwardly 60 from their lower surfaces, (see Fig. 6) are formed the horizontal slots 25. The said inner ends of the lever arms 22 and 23 are extended within the respective arms 15—15', 16—16', and in frictional contact with the 65 outer surfaces of the plates 20* 21* and are

secured to the ends of arms 15—15', 16—16' by the pivots 15* 16* respectively. The forward ends of the lever arms 22 and 23 extend past the pivots 15*—16* to effect an inward movement of the bars 20 and 21, and through 70 the upper portions of said ends extend the pivots 24, 24', which pivots also extend through the slots 25 in the respective bars 20 and 21, and which act to raise and lower and open the jaws 18 and 19 of the implement. 75

In a downward movement of the lever arms to the position seen in Fig. 4, the cams 24 on the lever arms act to close the jaws and hold them closed. Upon the lower outer 80 edge portion of the body 10, are the cap holding flanges 26, which are short in length and grooved at 26' on their inner surfaces.

The bottle sealing cap 27, as seen in Fig. 7, consists of a metal disk having a downwardly extended outwardly inclined crimped annular flange 27'. Upon the inner surface of the disk, is a packing 28, composed usually of cork, but other substances may be employed. 29 indicates the upper portion or 90 neck of a bottle, and 30 the groove at the upper end which receives the crimped flange 27 of the cap, the depression being seen at 31 in the cap. 95

In operation, the lever arms 22 and 23 are first raised in a vertical position, as seen in Fig. 1, in which position of said arms, the neck grasping jaws 18 and 19 are in an outward position, the pivots 24—24' in the outer ends of lever arms 22 and 23 being at 100 the outer ends of the slots 25 in the bars 20—21, the plunger 17 being in a downward position, as seen in Fig. 1, within the opening 14, in the neck 11 of the body 10 of the implement, its lower end extending a considerable distance within the opening 12 for the upper end of the bottle. 105

In this position of the operative parts of the invention, the bottle being upright upon the table, one of the sealing caps described 110 is inserted within the groove 26' of the flange 26, and the lever arms being grasped by the hands and the body 10 raised so that cap 27, which is held by the implement, is placed on the open end of the bottle. The 115 lever arms 22 and 23 are then moved downwardly by the hands until the jaws 18 and 19, which move inwardly by the contact of the upper portion of the curved ends or cams in contact with the outer edges of the 120 plates 20* 21*, grasp the neck of the bottle, in which movement the plunger 17 moves upwardly and also the jaws 18 and 19, automatically forcing the upper end of the bottle with its cap 27 within the opening 12 in the body 10 of the implement, to a position near the arched inner end 13 of said opening, thereby forcing the outwardly inclined crimped flange 27' of the cap inwardly within the groove 30, in the neck of the 130

bottle. The lever arms are now in a position, in their downward movement, at an angle to the jaws, as seen in Fig. 4. The cap now being secured to the end of the 5 bottle, the lever arms 20 and 21 are raised in position, the jaws still grasping the neck of the bottle, but moving downwardly so as to move the plunger 17 downwardly, its inner end being brought forcibly into contact with the cap 27, depressing the disk of 10 the cap and forcing the packing 28 into the opening in the neck of the bottle, as seen in Fig. 8, at the same time forcing the cap and bottle back out of the hollow body 10 of 15 the implement, thus effecting a complete sealing of the bottle, this being uniform in all bottles sealed by the implement. The lever arms being now raised into the vertical position, as seen in Fig. 1, the plunger 20 continuing to act upon the cap and raising the body 10 of the implement above the neck of the bottle while at the same time releasing the jaws 18 and 19, from the neck, completing the capping of the bottle.

25 The invention permits the capping of bottles to be made with rapidity and efficiency, thus economizing the time usually required in the operation.

Such modifications may be employed as 30 are within the scope of the appended claims.

Having fully described my invention, what I now claim as new and desire to secure by Letters Patent, is,

1. In combination, a movable hollow 35 bottle capping body for receiving and securing a cap to a bottle, pivoted levers actuating the said body to affix a cap to a bottle, grasping jaws controlled by the pivoted levers, and cap releasing means acting reciprocally upon a cap during releasing of the grasp of the bottle grasping jaws.

2. In combination, a hollow bottle capping body, operating levers pivoted to said body, bottle grasping jaws, and arms supporting said jaws, and controlled by said operating levers to impart a rising and falling action to said arms and the grasp and release of said jaws on a bottle, and cap releasing means pivoted to said arms acting reciprocally upon a cap to release the capping body from the cap during the release of the bottle grasping jaws.

3. In combination, a hollow bottle capping body, arms extending outwardly from 55 said body, operating levers pivoted to said arms, a cap releasing plunger, and means actuated by the said levers co-acting to impart reciprocation to said plunger.

4. In combination, a hollow bottle capping body, arms extending outwardly from

said body, operating levers pivoted to said arms, pivoted bars having cam engaging surfaces to which the inner ends of said levers are pivoted and adapted to engage with said cam engaging surfaces, and bottle 65 grasping jaws on said bars.

5. In combination, a hollow bottle capping body for receiving and securing a cap to a bottle, having a vertical opening, a cap releasing plunger in said opening, arms 70 extending outwardly from the sides of said hollow body, upright bars having inwardly bent upper ends pivoted to the upper end of said plunger, operating levers pivoted to said outwardly extended arms on said bottle 75 capping body, bottle grasping jaws on the lever ends of said upright bars, operable means on the inner ends of said levers and said bars acting to raise and lower, and communicate an inward reciprocal grasping 80 and releasing action to said jaws.

6. An implement for capping bottles, comprising a hollow body for receiving and securing a cap to a bottle, said body having a vertical opening extending within 85 said hollow body, a plunger therein, outwardly extended downwardly bent arms on opposing sides of said body spaced apart, outwardly and inwardly movable vertical bars having inwardly bent upper ends 90 pivoted to the upper end of said plunger and provided with slots at their lower ends, bottle grasping jaws on the lower ends of said bars, bar operating lever arms pivoted to the body supporting arms, and 95 pivots securing the inner ends of the lever arms to the arms on said body and extending through said slots in said vertical bars.

7. An implement for capping bottles, comprising a hollow body for receiving and 100 securing a cap to a bottle, said body having a vertical opening extending within said hollow body, a plunger therein, outwardly extended downwardly bent arms on opposing sides of said body spaced apart, outwardly and inwardly movable vertical bars having inwardly bent upper ends pivoted to the upper end of said plunger and provided with horizontal slots at their lower ends, bottle grasping jaws on the lower ends of 110 said bars, cam engaging surfaces on the sides of said bars, and bar operating lever arms pivoted to the body supporting arms and having cams on their inner ends engaging with said cam surfaces on said movable 115 bars, and pivots on the inner ends of said arms extending through said slots in said vertical bars.

CHARLES A. BUNKER.
